GAME PIECE SIMULATING A SAILBOAT

Joseph S. L. Wharton, Jr., Essex, Conn.

Application November 8, 1947, Serial No. 784,811

2 Claims. (Cl. 273—137)

1

This invention relates to a game piece simulating a sail boat for use in a game designed to enable the players to maneuver sailing yachts under conditions approximating those encountered in actual sailing races.

The chief object of the invention is to provide a game piece in the form of a miniature boat to serve as a model sailing yacht and be capable of assuming upright and heeling positions.

A feature of the invention consists in providing a game piece in the form of a model hull with a pivoted sail and a stationary rudder. A projecting element integral with the mast and protruding under the hull enables the yacht to be retained in upright position when the sail is cross-wise to the hull and in heeling position when the sail is at a lesser angle thereto.

For a fuller understanding of the invention, reference will be had to the following detailed description to be read in connection with the accompanying drawings in which

Fig. 1 illustrates, in part in perspective, a game board with which the game piece of the present invention may be employed;

Fig. 2 illustrates, in perspective, one of applicant's game pieces shown in upright position;

Fig. 3 shows, in perspective, said game piece in heeling position; and

Fig. 4 shows said game piece in an "exploded view."

Considering the drawings, similar designations referring to similar parts, numeral 11 designates a playing surface, which may be in the form of a board, made of wood, plastic or other suitable material, covered by a cork or similar mat adapted easily to receive pins or the like. If desired, an unbacked sheet material may be employed to act as the playing surface.

The surface bears a plurality of parallel lines 12, diagonally disposed at an angle to the sides 13, shown at 45 degrees in the drawings, each space bounded by such lines being a progression area.

The surface shown in the drawings illustrates (as by any suitable decorative or photographic means) a shore-line 14, with various land masses 15 positioned in and about a water area, generally designated 16. An island 17 is suitably located in the water area and harbor entrances 18 are provided as shown.

A compass rose 19 is preferably positioned on the island although it may be placed in any other suitable point on the surface. This not only shows the compass points but also indicates other conditions bearing upon the progress of

2

the game. A pointer 20 may be whirled in the usual way, during the course of play, to designate wind direction, squall conditions, etc. Instead of employing a compass rose, applicant contemplates the use of cards or other devices to designate similar playing conditions.

Buoys 21 may be fixed in position, as by imprinting or affixing of markers, or may be removably positioned as by separate markers 10 equipped with pins or the like, to designate one or more desired channels. The buoys are colored as in actual maritime use, to indicate the navigable channels.

Starting and course markers 22 may be fixed 15 or removable placed in position to indicate a prescribed racing course.

A game piece in the form of a power boat 23, of wood, metal, or other material, is provided, as shown, and may initially be positioned at a 20 starting point as, for example, dock 24, shown at the yacht club-house in the illustration.

A game piece in the form of a tow boat or other commercial vessel 25, also made of suitable material, is provided, as shown, and normally is 25 positioned at the entrance to channel 26, to be moved therethrough, as the play progresses.

Game pieces in the form of sailing yachts 27 consist of a hull 28, with an orifice therethrough in which is fitted a rotatable mast 29 having one or more sails integral therewith. At the bottom 30 of the mast 29 is a heeling member 30, transverse to the center line of the mast. The heeling member is attached to the mast in any desired manner so that it rotates therewith. Rudder 31 is fixed to the stern of the hull.

As shown in Fig. 2, the heeling member 30 is substantially in the same plane as the sails 32. As a result, when the sails are in "before the wind" position, that is, transverse to the center line of the boat, 33, then heeling member 30 will be transverse to the bottom or support point 34 of rudder 31. Thus, the sailing yacht will assume an upright position. However, when the sails, as shown in Fig. 3, are set in a reaching or "close haul" position, away from the wind, then heeling member 30 is relatively at a small angle to the hull and will not support the sailing yacht in an upright position. Yet, because the member is sufficiently long to afford support, it 50 will enable the sailing yacht to assume a heeling position, as illustrated.

While two or more players normally engage in a sailing contest in playing the game, each using one or more boats, it may also be played by one person.

While I have described a preferred embodiment of my invention, it will be understood my invention is not limited thereto since it may be otherwise embodied within the scope of the following claims.

I claim:

1. A game piece in the form of a sailing yacht comprising a hull, having an orifice therethrough, a rotatable mast member fitted in the orifice, a sail mounted on the mast member above the hull and rotatable with the mast member, and a heeling member attached to and rotatable with the mast placed below the hull, rotation of the mast varying the angle of the sail and the heeling member with respect to the keel of the hull whereby the yacht may assume a heeling position at one time and an upright position at another time.

2. A game piece in the form of a sailing yacht comprising a hull, a sail pivoted in the hull and a heeling member operatively associated with the sail, said heeling member being placed below the hull, manipulation of the sail varying the angle of the heeling member with respect to the keel of the hull whereby the yacht may assume

a heeling position at one time and an upright position at another time.
